HYDROGENATION OF STEAM CRACKED GASOLINE

Alan Arthur Yeo and John Norman Haresnape, Sunbury-on-Thames, England, assignors to The British Petroleum Company Limited, London, England, a joint-stock corporation of Great Britain
No Drawing. Filed Aug. 27, 1958, Ser. No. 757,446
Claims priority, application Great Britain Sept. 6, 1957
19 Claims. (Cl. 208—264)

This invention relates to an improved process for the partial hydrogenation of unsaturated gasolines.

It is known that some gasolines, for example gasolines obtained by steam cracking, contain gum forming constituents which impair the value of this material as a blending component for motor fuels.

It is an object of this invention to provide a process for improved unsaturated gasolines by hydrogenation. It is a further object to provide a process for improving the gum stability of gasolines. Other objects will appear hereinafter.

According to the present invention there is provided a method for improving a gasoline containing at least one diolefin and/or at least one styrene, which comprises passing said gasoline with hydrogen over a supported elemental nickel catalyst under conditions such that diolefins, if present, are hydrogenated to mono-olefins, and styrenes, if present, are hydrogenated to saturated side chain aromatics.

Preferably the severity of the conditions of hydrogenation is selected to provide a high percentage conversion of any diolefins present to mono-olefins and of any styrenes present to saturated side chain aromatics with a low percentage conversion of acyclic mono-olefins and of diolefins to saturated hydrocarbons. As is well known in the art, severity of hydrogenation can be increased by raising the hydrogen partial pressure, raising the reaction temperature, increasing the hydrogen/feedstock ratio or decreasing the flow rate.

According to a further feature of this invention it has now been found that the gum stability of a gasoline containing diolefins and/or styrenes, for example, a steam cracked gasoline, may be improved by hydrogenation over a supported elemental nickel catalyst, with only a small loss of octane number, by control of the amount of hydrogen thereby combined with unit weight of the gasoline feedstock. Thus according to this further feature of the invention there is provided a process which comprises continuously passing a gasoline which contains at least one diolefin or at least one styrene, said gasoline being, for example, a steam cracked gasoline which contains gum forming constituents, with hydrogen over a supported elemental nickel catalyst under hydrogenation conditions, the amount of hydrogen thereby combined with unit weight of the gasoline feedstock being controlled at a predetermined value such that the octane number, as hereinafter defined, of the product is at least as great or not substantially less than that of the gasoline feedstock.

Steam cracked gasolines not only contain such gum forming constituents as diolefins or styrenes, but are characterized further by the fact that they contain sulfur compounds. In the past, it has generally been recognized that sulfur-containing feed stock is unsuitable for use over an elemental nickel catalyst when the object is to achieve hydrogenation of dienes at low temperature. Un-

2

expectedly and surprisingly, however, the steam-cracked gasolines described herein do not de-activate the elemental nickel catalyst. On the contrary, the elemental nickel catalyst of the present invention remains highly active for long periods of time in achieving selective hydrogenation of the dienes contained in these gasolines which have been cracked at high temperatures.

- The desired amount of hydrogen to be combined with unit weight of the gasoline feedstock may be predetermined on the basis of a series of simple test runs. Thus it will be found that as this amount of hydrogen increases from zero value, the gum stability of the product will improve. Up to a certain amount of hydrogen (per unit weight of gasoline) this improvement will increase with increase in this amount of hydrogen and without substantial loss of octane number (between feedstock and product), while beyond this value there will be an increasing loss of octane number with increase in this amount of hydrogen; the optimum amount of hydrogen per unit weight of a given gasoline feedstock will be apparent from a series of tests covering a range of values. Control of the amount of hydrogen combined may be effected by variation of the reaction temperature, or reaction pressure or hydrogen/gasoline feedstock ratio.
- 25 The amount of hydrogen combined with unit weight of gasoline feedstock can be determined by measurement of the flow rate of hydrogen recovered in the process (flow rate of hydrogen in the feed gas and gasoline feed rate being known).
- 30 Gum stability may be measured by any of the methods known in the art, the Lauson rating being a very suitable method. The Lauson test is described in The Petroleum Engineer, vol. 27 at pages C19-C30 (November 1955).
- 35 Octane number of the product of test runs may be determined by any of the methods known in the art; the scale for the purpose of the present invention is a measurement of the unleaded octane number by the octane number (research) method as described in the ASTM 40 Manual for Rating Motor Fuels by Motor and Research Methods (1956).

The process of the present invention is suitable for treatment of gasolines boiling within the range 15° C. to 200° C. Suitably the gasolines are debutanised materials. Preferably the gasolines are free of hydrogen sulphide. Preferably the gasolines treated in accordance with the present invention have a total sulphur content of 0.005 to 0.04% by weight. The gasolines may be produced by cracking, in the presence of steam, petroleum distillate fractions, for example primary flash distillate or naphthas, boiling within the range 15° C. to 250° C. Particularly has the process of the invention been found to be beneficial in the treatment of gasolines produced by steam cracking under conditions favouring the production of olefins. Suitable cracking temperatures lie in the range 1100° F. to 1400° F. and suitable cracking pressures lie in the range 0 to 50 lbs./sq. in. gauge.

By the term "supported elemental nickel catalyst" we mean a catalyst which, after reduction, consists of elemental nickel on a catalyst base.

A preferred catalyst is elemental nickel-on-alumina. Preferably the alumina is present as gamma alumina. Suitable elemental nickel-on-alumina catalysts are prepared by the impregnation of solid alumina, in the form of wet or dry alumina gels, with a solution of an easily decomposable nickel salt, e.g. nitrate, acetate, formate, followed by drying the mixture and roasting at 500° C.

for 2 hours. A typical catalyst containing 10% nickel by weight of the finished catalyst is obtained by impregnating 400 grams of $\frac{1}{8}$ " (one eighth inch) alumina pellets with a solution of 220 grams of nickel nitrate hexahydrate in 75 ml. of water. The mixture is dried at 140° C. for 8-16 hours and roasting at 500° C. for 2 hours.

Preferably, however, the elemental nickel-on-alumina catalysts are produced by mixing together finely divided nickel compound and finely divided alumina and pelletizing. Mixing may be carried out wet or dry and preferably by ball milling.

Before use, the supported elemental nickel catalyst as prepared above requires activation. This is conveniently carried out by heating the catalyst (e.g. in situ in the plant reactor) at 150 to 600° C. preferably about 250° C. in a stream of hydrogen or hydrogen containing gas, at a pressure in the range 0 to 200 p.s.i.g., for up to three days. The temperature is preferably maintained at 200-300° C. and the pressure at atmospheric. When the catalyst is prepared from nickel formate, activation may be carried out by heating at 150° C.-300° C. in an inert gas stream. After pre-treatment the catalyst will usually be pyrophoric.

Preferably catalysts employed in the process herein described are silica-free.

If desired hydrogenation may be carried out using a gas consisting of hydrogen together with inert constituents. Preferably, when inert constituents are present, the gas contains at least 25 mol percent of hydrogen, the proportion suitably lying within the range 25-90 mol percent of hydrogen.

A preferred gas is a platformer tail gas. Suitably a gas is employed containing 70 mol percent of hydrogen. A typical gas will consist of 70 mol percent of hydrogen and 30 mol percent of methane. Other suitable gases are steam cracker tail gas, catalyst cracker tail gas and tail gas derived from the dehydrogenation of hydrocarbons.

The hydrogenation may conveniently be carried out at a temperature in the range 0° to 200° C. and at a pressure in the range 0 to 1000 p.s.i.g. A suitable space velocity is 1-6 vol./vol./hour for example 2 vol./vol./hour. Usually a vertical reactor, operating under down-flow, is employed.

Preferred operating pressures lie in the range 200-300 lbs./sq. in. gauge. When using pressures in this range, gas mixtures having a hydrogen content of 50-90 mol percent are very suitable. Thus a gas containing 70 mol percent of hydrogen can be used with advantage.

Operating conditions are preferably selected to ensure that the hydrogen partial pressure is at least 100 lbs./sq. in. gauge.

Preferred operating temperatures lie in the range 80-180° C.

Gas is preferably separated from the liquid product at a temperature below 40° C.

In general, using high hydrogen content gases, part of the tail gas will be recycled, the remainder being withdrawn to prevent the build-up of inerts from reaching an undesirably high level. Preferred gas recycle rates (including make-up gas) lie in the range 300-700 s.c.f./b., preferably being about 500 standard cubic feet per barrel (s.c.f./b.) of feedstock.

Typical hydrogen consumption rates lie in the range 60-140 s.c.f./b. preferably being about 100 s.c.f./b.

Preferably the hydrogen absorption is controlled to limit the loss of octane number (research clear) to below 0.8; it has been found that, under these conditions, the hydrogen absorption will lie in the range 50 to 150 s.c.f./bbl. Thus, according to a preferred manner of operation, the hydrogenation conditions are controlled to maintain the hydrogen absorption rate within this range.

In general, the hydrogen treated product will be stabilized, by distillation, to give a product of low C₄ content, usually less than 1% by weight. The product may also be re-run to establish desired end-point, for example, an ASTM end point of 205° C.

Spent catalyst may be pyrophoric and should be steam purged before being discharged.

The invention is illustrated but in no way limited with reference to the following examples.

EXAMPLE 1

Steam cracker gasoline of petroleum origin was passed with hydrogen over a nickel-on-alumina catalyst containing 10% by weight of nickel.

This gasoline before treatment had the following characteristics:

Specific gravity	-----	0.7675
ASTM distillation:

Hydrogen absorption rates during the initial period (0-3 hours), are high. This results from the use of a freshly prepared catalyst and the values are thus not representative of steady running conditions.

EXAMPLE 3

Steam cracker gasoline, of petroleum origin, containing dienes and styrene homologues was passed with a hydrogen/methane gas mixture, having a H₂/CH₄ mol ratio of 1/3, over a nickel-on-alumina catalyst containing 10% by weight of nickel. The gasoline had the characteristics shown in Table 3.

EXAMPLE 5

A catalyst consisting of nickel deposited on magnesium oxide was prepared in the following manner: 400 grams of magnesium oxide (commercial heavy grade passing 100 BSS mesh) was mixed with 137 grams of nickel formate powder by sieving until homogeneous. The mixture was converted to $\frac{1}{8}$ " (one-eighth inch) x $\frac{1}{8}$ " (one-eighth inch) pellets and activated by treatment with hydrogen for four hours at 250° C.

Steam cracker gasoline of petroleum origin was passed with hydrogen over the activated catalyst. The gasoline had the characteristics shown in Table 6; operating conditions and results obtained are shown in Table 7.

EXAMPLE 6

A catalyst consisting of nickel deposited on alumina was prepared in the following manner:

368 grams of alumina (commercial 6-12 BSS mesh) was heated to 140° C. for 30 minutes. The hot alumina was impregnated with a solution of 200 grams nickel nitrate (hexahydrate) in 70 mls. of water and dried at 140° C. The impregnated alumina was roasted at 500° C. for two hours.

The roasted catalyst was activated by treatment with hydrogen at 500° C. for 16 hours.

Steam cracker gasoline of petroleum origin was passed with hydrogen over the activated catalyst using hydrogen recycle.

The pressure was maintained at 135 lbs./sq. in. gauge; the hydrogen recycle rate was 500 s.c.f./bbl. and the liquid feed rate 2 vol./vol./hour.

The gasoline had the characteristics shown in Table 8; operating conditions and results obtained are shown in Table 9.

The product obtained during the period 710-750 hours

was distilled with removal of 3% by wt. bottoms. Results specified are for the re-run product.

We claim:

1. A process for improving a gasoline produced by cracking a petroleum fraction at a temperature above 1100° F. and containing at least one unsaturated hydrocarbon selected from the group consisting of diolefins and styrenes, which comprises passing said gasoline with hydrogen over a supported elemental nickel catalyst under hydrogenation conditions of temperature in the range 0° to 200° C., pressure in the range 0-1000 p.s.i.g. and space velocity in the range 1-6 vol./vol./hr., the hydrogenation conditions being selected within said ranges such that diolefins are hydrogenated to mono-olefins, and styrenes are hydrogenated to saturated side chain aromatics, without appreciable conversion of acyclic mono-olefins to saturated hydrocarbons and without appreciable lessening of the octane number of the feedstock.

2. A process as specified in claim 1 in which the gasoline is of petroleum origin and boils within the range 15-200° C.

3. A process as specified in claim 1, in which the steam cracked gasoline has been produced by cracking at a temperature in the range 593-760° C. and at a pressure in the range 0-50 lbs./sq. in. gauge.

4. A process as specified in claim 3, in which the alumina is employed as gamma-alumina.

5. A process as specified in claim 1 in which the supported elemental nickel catalyst is an elemental nickel-on-alumina catalyst.

6. A process as specified in claim 1 in which the gas employed for hydrogenation consists of hydrogen together with inert constituents.

7. A process as specified in claim 6, in which the gas contains at least 25 mol percent of hydrogen.

8. A process as specified in claim 7, in which the gas contains 25-90 mol percent of hydrogen.

9. A process as specified in claim 6, in which the gas is a plattformer tail gas.

10. A process as specified in claim 6, in which the gas is a mixture consisting predominantly of a mixture of hydrogen and methane.

11. A process as specified in claim 1, in which the hydrogenation is carried out at a temperature in the range 80-180° C.

12. A process as specified in claim 1, in which the hydrogenation is carried out at a pressure in the range 200-300 lbs./sq. in. gauge.

13. A process as specified in claim 12, in which the gas used for hydrogenation contains inert constituents and 50-90 mol percent of hydrogen.

14. A process as specified in claim 13, in which the hydrogenation is carried out at a hydrogen partial pressure of at least 100 lbs./sq. in. gauge.

15. A process as specified in claim 1, in which the hy-

drogenation is carried out with recycle of tail gas at a gas recycle rate in the range 300-700 s.c.f./b.

16. A process as specified in claim 1, in which the hydrogenation conditions are selected to give a hydrogen absorption per pass in the range 50-150 s.c.f./bbl.

17. A process as specified in claim 1, in which the gasoline has a total sulphur content in the range 0.005 to 0.04% by weight.

18. A process for improving a gasoline produced by cracking a petroleum fraction at a temperature above 1100° F. and containing acyclic mono-olefins and at least one unsaturated hydrocarbon selected from the group consisting of diolefins and styrenes, which comprises passing said gasoline with hydrogen over a supported elemental nickel catalyst under hydrogenation conditions of temperature in the range 0° to 200° C., pressure in the range 0-1000 p.s.i.g. and space velocity in the range 1-6 vol./vol./hr., the hydrogenation conditions being selected within said ranges to provide a high percentage conversion of diolefins to mono-olefins, a high percentage conversion of styrenes to saturated side chain aromatics and a low percentage conversion of acyclic mono-olefins to saturated hydrocarbons without appreciable lessening of the octane number of the feedstock.

19. A process for improving a gasoline produced by cracking a petroleum fraction at a temperature above 1100° F. and containing at least one unsaturated hydrocarbon selected from the group consisting of diolefins and styrenes, which comprises continuously passing said gasoline with hydrogen over a supported elemental nickel catalyst under hydrogenation conditions of temperature in the range 0° to 200° C., pressure in the range 0-1000 p.s.i.g. and space velocity in the range 1-6 vol./vol./hr., the hydrogenation conditions being selected within said ranges to fix the amount of hydrogen thereby combined with unit weight of the gasoline feedstock at an amount in the range 50-150 s.c.f./b. such that the octane number of the product is not substantially less than that of the gasoline feedstock.

UNITED STATES PATENT OFFICE
CERTIFICATE OF CORRECTION

Patent No. 3,024,188

March 6, 1962

Alan Arthur Yeo et al.

It is hereby certified that error appears in the above numbered patent requiring correction and that the said Letters Patent should read as corrected below.

Column 1, line 19, for "improved" read -- improving --; column 3, line 37, for "catalyst" read -- catalytic --; column 7, Table 9, under the heading "Time on stream (hours)", line 11 thereof, for "Accelereted" read -- Accelerated --; column 8, Table 11, in the heading to column 1 thereof, for "Steam" read -- Stream --; same Table 11, heading to the fourth column, for

950-1,0	read	950-
1,050		1,050

same table, last column, the second entry "115" should be dropped down one space so as to appear opposite "102", in the fifth column; same column 8, line 29, for "hyydrogen" read -- hydrogen --.

Signed and sealed this 14th day of August 1962.

(SEAL)
